UNITED STATES PATENT OFFICE.

AUGUST MATITSCH, OF NOTTINGHAM, ENGLAND, ASSIGNOR TO THE FIRM OF M. FABER & CO., OF VIENNA, AUSTRIA-HUNGARY.

BOBBIN FOR MACHINES FOR THE MANUFACTURE OF PILLOW-LACE.

1,113,671.

Specification of Letters Patent.

Patented Oct. 13, 1914.

Application filed November 18, 1912. Serial No. 732,045.

To all whom it may concern:

Be it known that I, AUGUST MATITSCH, a subject of the Emperor of Austria-Hungary, residing at Nottingham, England, 5 have invented Improvements in Bobbins for Machines for the Manufacture of Pillow-Lace, of which the following is a specification.

In machines for the manufacture of pillow lace slight shocks occur, in the same manner as in bobbin net lace making machines, during the movements of the bobbin slides through the combs at each reversal of the movement. These shocks are transmitted to the bobbins of the slides and cause them to continue to rotate with a step by step motion. Whereas however in the bobbin net lace making machines these shocks take place alternately in opposite directions 10 and therefore mutually neutralize each other in their action on the bobbins, it is necessary in pillow lace making machines to always put certain of the slides out of action during a number of successive revolutions and 15 therefore hold them back in one and the same outer comb so that in consequence the bobbin of a particular slide receives an impulse in the same direction at each revolution. When the impulses cause the bobbin 20 to rotate each time in the direction in which the thread is unrolled the particular bobbin thread will be slackened, owing to the continuous rotary motion of the bobbin, during its exit from the slide in such 25 a way that it will curve in any direction and form a long loose loop which is apt to catch in a neighboring slide so that the bobbin will be pulled out of its slide.

By means of a holding spring which acts 30 upon the slide bobbin and as is well known acts differently upon the bobbin according to whether it is fully wound or has had a somewhat large amount of thread unrolled from it, it is impossible to prevent the bobbin 35 from continuing to rotate owing to the shocks to which the slides are subjected when their movements are arrested. By means of a second spring placed in the slide it is possible to prevent the thread from 40 coming up out of the slide after it has been unwound by the said rotation of the bobbin

but the thread is still able to project from the side of the bobbin and before mentioned injurious loop formation still takes place.

According to this invention, for the purpose of obviating the said disadvantage the periphery of each bobbin is polygonal in shape so that the braking action of the holding spring that bears thereon is rendered 55 more efficient than if the periphery were cylindrical, and the formation, owing to shocks arising during the movements of the bobbin slide, of a loop in the length of thread passing from the bobbin to the clamping spring, 60 65 is prevented.

Figure 1 of the accompanying illustrative drawing shows a bobbin according to this invention detached from its slide. Fig. 2 shows the bobbin inserted in a bobbin slide. 70

The bobbin *s* has a polygonal periphery which form renders more efficient the braking action of the pressure spring *d* which has one end so fixed in the slide *a* that its free end bears on the said periphery to such 75 a degree that when the tension thereof is correct the corners of the bobbin cannot rotate under shock past the spring. The unwinding of the thread which is caused by the shocks is then so slight that loosening 80 and emergence of the thread under the thread hole in the form of a loop and consequently the pulling of the bobbin out of its slide cannot take place.

It will be noted that the corners formed 85 by the polygonal shape of the bobbin periphery act on the holding spring *d* as teeth or very slight projections to retard the rotation of the bobbin in its seat in the slide or carriage.

I claim—

1. A thin lace-machine bobbin, whose edges are provided with a large number of projections, in combination with a retaining spring arranged to engage said edges, the 95 limit of idle motion being determined by the distance between said projections.

2. A thin lace machine bobbin having polygonal ends of many sides in combination with a retaining spring and in frictional 100 engagement with a bobbin carriage.

3. A thin lace machine bobbin having

polygonal ends, the corners of said ends operating as rotation retarding means and the length of the sides proportioned in accordance with the permissible slack.

5. The combination of a lace machine carriage having a circular bobbin seat, of a bobbin therein having polygonal ends and a spring engaging the edges of said ends.

5. A lace machine bobbin having polygonal ends and approaching a circle in shape. 14
Signed at Nottingham England this ninth day of November 1912.

AUGUST MATITSCH.
